DESIGN FOR A CIGARETTE DISPENSER

Victor S. Reynolds, Detroit, Mich., assignor to
J. E. Gould, Detroit, Mich.

Application October 29, 1945, Serial No. 123,267

Term of patent 3½ years

(CL. D85—2)

To all whom it may concern:

Be it known that I, Victor S. Reynolds, a citizen of the United States, residing at Detroit, Wayne County, Michigan, have invented a new, original, and ornamental Design for a Cigarette Dispenser, of which the following is a specification, reference being had to the accompanying drawing, forming a part thereof, in which:

Fig. 1 is a front perspective view of a cigarette dispenser showing my new design;

Fig. 2 is a top plan view of the cigarette dispenser shown in Fig. 1;

Fig. 3 is a side elevation; and

Fig. 4 is a front elevation of the cigarette dispenser shown in Fig. 1.

I claim:

The ornamental design for a cigarette dispenser, as shown.

VICTOR S. REYNOLDS.
